UNITED STATES PATENT OFFICE.

FRANZ SKAUPY, OF BERLIN, GERMANY, ASSIGNOR TO GENERAL ELECTRIC COMPANY,
A CORPORATION OF NEW YORK.

ELECTRIC INCANDESCENT LAMP AND METHOD OF MANUFACTURING ITS ILLUMINATING BODY.

Application filed December 2, 1921, Serial No. 519,400, and in Germany December 4, 1920.

This invention relates to an electric incandescent lamp in which transparent bodies which are as free of turbidness or dimness as possible and are colored preferably corresponding to that portion of the spectrum which in its turn corresponds to the rays to be emitted are caused to glow. As in most cases these bodies themselves are not sufficiently conductive, they are united with a metallic conductor that serves as carrier for the current and transfers the current-heat to the transparent part of the illuminating body, the union being effected in a manner ensuring good transfer of the heat, preferably by applying the metallic conductor to the transparent conductor in the form of a thin small layer either upon the outer surface or, if the transparent conductor is of tubular shape, upon the inner surface of the same also. As a metallic conductor has a comparatively uneconomical radiation which extends over all portions of the spectrum including some which are undesirable, its radiating surface must be as small as possible in order to make its rays practically insignificant in comparison to those of the transparent colored part of the illuminating body and to make it serve mainly for the current-conduction and the heat transference, so that the chief amount of the radiation issues from the transparent part. The metallic conductor, in order to be able to transfer the heat as uniformly as possible to all portions of that transparent part should not be too distant from any portion of the illuminating body. That is attained best by making the metallic conductor form a spiral upon the transparent part, the arrangement being then preferably such that the axis of the spiral coincides with the axis of the illuminating body.

In devices of the prior art either opaque metallic or opaque non-metallic illuminating bodies for instance oxidic bodies, have been used, the main radiation of which, with the temperatures mostly employed, lies for the greater part in the invisible portion of the spectrum, whereby the greatest part of the energy spent is consumed in the production of rays of an undesirable wave length. But lamps manufactured according to the present invention have a pure or nearly pure selective radiation which is the more economic the less the illuminating substance employed absorbs and emits waves of an undesirable length and the smaller the radiating surface of the metallic conductor is by which the current heat is transferred. It might, thus, on principle, be possible to produce a nearly absolutely economic lamp in which nearly the total of the electric energy spent is transformed into radiation of the desired wave length, that is to say (apart from special cases where invisible light, for instance ultra-red light, is to be converted) into visible light.

The transparent substances existing in nature or capable of being manufactured in a chemical way, are unsatisfactory because they emit light of an undesirable wave length and contain turbidities, impurities and the like which radiate dark waves. Nevertheless, there may be substances found which are sufficiently free from this drawback and yield a satisfying output of light, especially if such substances are suitably colored by admixtures of slight quantities of substances of another color. To prevent the coloring substances from rendering the transparent substance opaque, they must either already exist in their base substances in the form of a solid solution or an isomorph admixture or in a highly dispersed colloidal state, especially near to and at the surface of the respective base-substances, or must be applied to the outer surface of the same.

My invention contemplates the use of moderate temperatures of the illuminating body.

To obviate structural changes of the illuminating body by the high temperature whereby the transparency would be diminished and the illuminating effect changed, as easily occurs with glassy substances or with substances forming small crystals, the transparent part of the illuminating body may be manufactured, according to this invention, from one crystal or from a few crystals or crystal pieces, similarly as done with the wolfram crystal thread in the manufacture of incandescent lamps. One chooses crystals that are free from turbidness or dimness, also as free as possible from the Tyndall phenomenon, and transparent; they may be colored by admixtures and shaped as desired and required, by melting. To manufacture them, similar methods may advantageously be employed as are made use of

for the manufacture of artificial precious stones, for instance rubies. Or pulverulent substances may be pressed to form little bars which are heated to such a high temperature as to completely sinter until they become transparent. The heating is preferably carried through in a vacuum, either by means of an external source of heat, for instance an electric furnace, or by electric heating of the little bar itself which is rendered conductive either by pre-heating it or by a heat-conducting connection with a metallic conductor. This latter may be the same as that serving in the finished lamp for transferring the current heat. If the bar itself is made conductive, substances may be added which first increase its conductivity and then evaporate at high temperature. The heating is in such a case effected preferably by alternating current of a rather high frequency, of the order employed in wireless telegraphy, the purpose being to obviate electrolytic phenomena. The resulting transparent body should, from obvious reasons, be as free as possible from electrolytic conduction. In cases where a certain conductivity of the transparent body cannot be obviated, the metallic conductor is preferably arranged in the form of a few axial strips either upon the surface of its base or within this latter, the axial strips being in either case connected in parallel with each other.

As transparent substances suitable for the purpose in question, heat-proof oxides, nitrides, carbides, sulphides, flourides, and especially such substances as oxide of thorium, oxide of scandium, oxide of magnesium, and the like may be employed; furthermore the corresponding nitrides, also boron-nitrogen. As coloring substances suitable for the purpose in question may be employed fire-proof oxides, such as oxide of cerium, especially, however, substances which in a thick layer show metallic brightness, but are transparent and colored in a thin layer, as is the case with the nitrides of titanium, zirconium, some low oxides, such as that of titanium, but also with certain metals themselves.

The metallic conductors which are the intermediaries for the transfer of the heat to the transparent substance consists of metals or conductive compounds of high fusing point, such as tungsten, osmium, tantalum graphite, titanium-nitrogen, and the like. The layers or coatings consisting of them, for instance spirally wound coatings, may be made by applying to the transparent substance a colloidal solution of the respective conductor in the form of a small strip and then heating the whole body in a suitable atmosphere in order to sinter it. Instead of the colloidal solution of the conductor a solution of an easily reducible compound of the respective substance may be made use of,

for instance colloidal wolfram acid, and the coating may be subsequently converted into metal by heating it in a reducing atmosphere. Coatings of the kind in question may also be applied by cathodic dispersion. The coatings may also be applied by those methods that are made use of for producing thin metallic layers.

In order to make my invention more clear, I refer to the accompanying drawing, in which Figure 1 is a side-view of an electric incandescent lamp manufactured according to this invention. Figure 2 is a similar illustration showing the lamp provided with another form of construction of the illuminating body; and Figure 3 is also a similar illustration showing a third form of execution.

Referring to Fig. 1, a transparent little bar of oxide of thorium is provided with a spirally shaped coating or layer of tungsten or osmium, the ends of which are conductively connected with the feed wires 3 and 4 of the bar 1. The spaces between the convolutions of the spiral 2 and the bar 1 are covered with a thin transparent coating or layer of titanium-nitride. The ends 6 of the illuminating body are appropriately thickened in order to prevent the feed wires from becoming as hot as the effective parts of the illuminating body, because said ends, otherwise, would radiate away too large an amount of energy. For the rest, concerning the connection of the feed wires with the illuminating body, for instance with the metallic layer of this latter, all the methods known in connection with the manufacture of Nernst-lamps may be employed.

If the transparent base substance of the illuminating body, which carries the metallic conductor, is not or cannot be, sufficiently colored, transparent colored substances of macroscopic dimensions may be embedded into, or made to contact with the outside of it. Several substances of different colors may be embedded into the same base substance, those substances emitting them, according to their colors, a correspondingly differently colored light whereby particular effects may be produced.

Corresponding to the chemical properties of the illuminating body the same may be made to light in the free air, in evacuated vessels or in vessels filled with gases of the proper kind. The bulbs are filled with gases that are bad conductors of heat, for instance argon gas and the like, or with a gas for instance nitrogen, which counteracts by its partial pressure the dissociation of the substance of the illuminating body, especially in the case where a nitride forms part of the illuminating body.

The conductor which transfers the heat may be a wire, if it is brought into suitable heat conducting relation with the transparent substance by being melted or pressed

into, or being made to contact with the outside of it.

As the illuminating bodies constructed according to this invention emit in most cases per unit of surface a by far lesser amount of energy than do the known illuminating bodies of incandescent lamps, they may be considerably larger than these latter, concerning their breadth, as well as their thickness. And as the current is supplied not through the transparent main portion of the conductor, but through the metallic conductor, the former may have the most varied forms; it may be a disk, a ball, a figurative representation, writing characters of any kind, and the like, and the various transparent parts may be made to light with different colors. At any rate, the lamp emits a mild, not dazzling light and is in this respect somewhat similar to electric gas lamps with glow discharge.

Fig. 2 shows a lamp, the illuminating body of which is a lens-shaped disk 7 around which the current conducting layer runs in a spirally-shaped way. The lamp shown in Fig. 3 has an illuminating body with parallel axial strips 8. No potential difference can arise between these strips and, consequently no transverse current can pass through the illuminating substance.

I claim:

1. In combination, a body which when heated radiates selectively and which is substantially transparent to waves differing from those radiated, and means for heating said body to cause it to so radiate.

2. In combination, a body which when heated radiates selectively and which is substantially transparent to waves differing from those radiated, the major portion of the selective radiation falling within the visible range of the spectrum and means for heating said body to cause it to so radiate.

3. In combination, a body in macro-crystal form which when heated radiates selectively and which is substantially transparent to waves differing from those radiated, and means for heating said body to cause it to so radiate.

4. In combination, a body in macro-crystal form which when heated radiates selectively substantially the major portion of the energy imparted to it by heating, and a device for heating said body to cause it to so radiate.

5. In combination, a body which when heated radiates selectively, said body being clear and in macro-crystal form, and means for heating said body to cause it to so radiate.

6. In combination, a body which when heated radiates selectively, said body being in transparent macro-crystal form, the major portion of the selective radiation falling

within the visible range of the spectrum, and means for heating said body to cause it to so radiate.

7. In combination, a body having the form of a transparent macro-crystal, and having the property of selectively radiating light when heated, means supported by said first body for heating the latter to cause it to so radiate.

8. In combination, a body in the form of a clear macro-crystal, said body having the property of selectively radiating light when heated, means supported by said body for heating the latter to cause it to so radiate.

9. In combination, a clear body which when heated radiates selectively, and electric means for heating said body to cause it to so radiate.

10. In combination, a body which when heated radiates selectively and which is substantially transparent to waves differing from those radiated, and means for heating said body to cause it to so radiate, said body consisting of a thorium compound.

11. In combination, a body which when heated radiates selectively and which is substantially transparent to waves differing from those radiated, and means for heating said body to cause it to so radiate, said body consisting of an oxide of a metal.

12. In combination, a body which when heated radiates selectively, and which is substantially transparent to waves differing from those radiated, and means for heating said body to cause it to so radiate, said body consisting of a compound of one of the metals which has a high fusing point.

13. In combination, a transparent body, a second body in intimate thermal contact with said first body, which second body when heated radiates selectively and is substantially transparent to waves differing from those radiated, and means for heating said first body to cause it to heat said second body to cause the second body to so radiate.

14. In combination, a transparent body, a second body supported by said first body, which second body when heated radiates selectively and which is substantially transparent to waves differing from those radiated, and means for heating said first body to cause it to heat said second body to cause the second body to so radiate.

15. In combination, first a transparent body, second a body in intimate thermal contact with said first body, which second body when heated radiates selectively and is substantially transparent to waves differing from those radiated, and means for heating said first body to cause it to heat said second body to cause the second body to so radiate, said second body consisting of a metallic oxide.

16. In combination, first a transparent body, second a body in intimate thermal con-

- tact with said first body, which second body when heated radiates selectively and is substantially transparent to waves differing from those radiated, and means for heating 5 said first body to cause it to heat said second body to cause the second body to so radiate, said second body consisting of a compound of one of the metals which has a high melting point.
- 10 17. In combination, first a transparent body, second a body in intimate thermal contact with said first body, which second body when heated radiates selectively and is substantially transparent to waves differing from those radiated, and means for heating 15 said first body to cause it to heat said second body to cause the second body to so radiate, said second body consisting of a substance which in a thick layer has a brilliant metallic 20 color and which in a thin layer is transparent and colored.
18. In combination, first a transparent body, second a body supported by said first body, which second body when heated radiates selectively and which is substantially transparent to waves differing from those radiated, and means for heating said first body to cause it to heat said second body to cause the second body to so radiate, said 25 second body consisting of a substance which in a thick layer has a brilliant metallic color and which in a thin layer is transparent and colored.
19. In combination, first a transparent body, second a transparent body in intimate thermal contact with said first body, which second body when heated radiates selectively and which is substantially transparent to waves differing from those radiated, a major 30 portion of the selective radiation falling within the visible range of the spectrum, and means for heating said first body to cause it to heat said second body to cause the second body to so radiate.
- 40 20. In combination, first a transparent body, second a body in intimate thermal contact with said first body and which when heated radiates selectively the major portion of the energy imparted to it by heating, and means for heating said first body to cause it to heat said second body to cause the second body to so radiate.
21. In combination, first a transparent body, second a body supported by said first body, which second body when heated radiates selectively the major portion of the energy imparted to it by heating, and means for heating said second body to cause it to so radiate.
22. The method of preparing a transparent crystal which is a poor conductor of electricity and which has an absorption band in the visible range of the spectrum, which consists in adding to the material from which the crystal is made a substance which is volatile at high temperatures to render the material conductive and in passing a high frequency alternating current through said material until it is sintered and heating until the conducting substance volatilizes.
23. In combination, a body which when heated radiates selectively, and which is substantially transparent to waves differing from those radiated, and means for heating said body to cause it to so radiate, said body consisting of a compound of one of the refractory metals which has a high fusing point.
24. In combination, first a transparent body, second a body supported by said first body, which second body when heated radiates selectively and which is substantially transparent to waves differing from those radiated, and means for heating said first body to cause it to heat said second body to cause the second body to so radiate, said second body consisting of cerium oxide.

In testimony whereof I affix my signature.

FRANZ SKAUPY.
